UNITED STATES PATENT OFFICE.

JOSEPH LEDWINKA, OF PHILADELPHIA, PENNSYLVANIA, ASSIGNEE TO EDWARD C. BUDD MANUFACTURING COMPANY, OF PHILADELPHIA, PENNSYLVANIA, A CORPORATION OF PENNSYLVANIA.

COAL-WAGON BODY.

1,190,429.

Specification of Letters Patent. Patented July 11, 1916.

Application filed November 22, 1912. Serial No. 732,834.

To all whom it may concern:

Be it known that I, JOSEPH LEDWINKA, a citizen of the United States, residing at Philadelphia, county of Philadelphia, State 5 of Pennsylvania, have made a certain new and useful Invention in Coal-Wagon Bodies, of which the following is a specification.

This invention relates to coal wagon bodies.

10 The object of the invention is to provide a coal wagon body which is simple in construction, strong and durable and economical to manufacture.

A further object of the invention is to 15 provide a sheet metal body for coal wagons and similar vehicles, and to strengthen and render the same rigid and capable of withstanding the rough usage to which such devices are subjected.

20 Other objects of the invention will appear more fully hereinafter.

The invention consists substantially in the construction, combination, location and relative arrangement of parts, all as will 25 be more fully hereinafter set forth, as shown in the accompanying drawing and finally pointed out in the appended claim.

In the accompanying drawing,—Figure 1 is a view in side elevation showing a construction of coal or other wagon body embodying the principles of my invention. Fig. 2 is an end view of the same. Figs. 3, 4, 5, 6, 7 and 8 are detail views in section on the lines 3; 4, 4; 5, 5; 6, 6; 7, 7; 8, 8, respectively, of Fig. 1. Fig. 9 is a broken detail view in plan of the upper corner of the vehicle body showing a strengthening gusset.

In one form of wagon employed for the 40 delivery of coal, sand, grain, and other materials, the body thereof is, generally, in the form of a hopper, the side and end walls thereof converging downwardly toward the center of the bottom, at which point a delivery spout communicates with the interior of the body. The present invention relates to bodies of this general type. Wagon bodies of this type employed for the purposes stated are subjected to rough usage 45 and as a consequence thereof are rapidly worn out, injured, dented or destroyed.

It is among the special purposes of my present invention to provide a wagon body

of the character and type referred to which is strong and durable and capable of withstanding the rough usage to which such bodies are subjected.

In carrying out my invention I form the body of sheet metal plates suitably assembled and secured together to form the body, 60 and I render such body rigid and increase the strength thereof by stiffening ribs of channel formation, suitably applied at the proper points, and at the corners or bends of the body I provide curved connecting 65 plates and secure all parts together by welded joints, thereby, in effect, producing a substantially integral, efficiently strengthened and channel ribbed body, shaped to the desired hopper contour and having a 70 delivery opening at the bottom thereof.

Referring to the accompanying drawing and to the various reference numerals appearing thereon 10, 11, designate, respectively the vertical portions of the side and 75 end sheet metal plates composing the body of the wagon, and 12, 13, designate, respectively, the downwardly inclined or converging side and end portions of the sheet metal plates. These sheet metal plates are cut and 80

shaped to the required form to produce when assembled together the wagon body and to form the hopper shape or outline thereof, as shown. If desired, where the vertical and downwardly inclined portions of the side 85 and end plates are separate from each other, they are joined by a suitably curved junction plate 14, see Figs. 3, 5 and 7, to form the corners, or bends of the body structure, the edges of the junction plates being welded to 90

the respectively proximate edges of the portions 10, 11; 10, 12; or 10, 13, as the case may be. In order to strengthen and render more rigid and sturdy the sides and ends of the wagon body I propose to apply thereto suitable ribs formed of sheet metal and suitably bent into channel formation. Such strengthening ribs are shown at 15, and are in the form of substantially U shaped channels flanged at their edges, as indicated at 16, 100 which are applied flatwise against and preferably welded to the outer surface of the body plates 11, 12, 13. In practice I prefer to form the strengthening channel ribs with a longitudinal taper, as clearly shown in 105 Fig. 2, the taper being toward the upper

ends. I also propose to bend the ribs 15, intermediate their ends so that they will conform to the vertical and downwardly inclined sides or hopper shape thereof. In order to secure strength and rigidity at the upper edges of the body, I form edge ribs 17, in the form of nearly closed channels, the edges of the vertical portions of the side and end plates 10, 11, being received between the lips 18, 19 of said edge ribs and welded therein, as seen most clearly in Fig. 8. The downwardly inclined body plates 12, 13 converge toward a delivery opening at the lowest part of the body. In practice I prefer to employ two delivery openings, as indicated at 20, 21, respectively directed toward opposite sides of the body, so that the contents of the body may be delivered to either side from the wagon. If desired, chute sections 22, may be hinged or otherwise connected to the delivery spouts 20, 21, so as to direct the material delivered from the wagon body to any desired point, such, for instance, as into a vault opening in a sidewalk where coal is the material delivered. When not required for use the chute sections 22, may be rocked up against the side of the wagon body and secured by any convenient means, such as a hook 23, and ring 24. If desired, and as shown at 40, Fig. 9, a gusset plate may be placed inside the corners of the body at the upper edges thereof and secured, respectively, to the side and end walls thereof, for strengthening purposes. Similarly a gusset plate 41, may also be placed inside the body at the angle between

the vertical and downwardly inclined portions thereof, as indicated on Fig. 2.

The wagon body may be supported upon or carried by any suitable or convenient frame or chassis, and in any suitable or convenient manner. I have shown a portion of such a frame or chassis at 25, with supporting standards 26 therefrom for carrying the wagon body.

Having now set forth the object and nature of my invention, and a construction embodying the principles thereof, what I claim as new and useful and of my own invention, and desire to secure by Letters Patent is:—

A wagon body composed of sheet metal plates having vertical side and end portions and downwardly inclined or converging bottom portions and strengthening ribs channel shape in cross section secured to the exterior surfaces of said plates, said ribs being bent intermediate their ends to conform to the angle between the vertical and inclined portions of the body, one portion of each rib extending vertically against a side plate and the other portion thereof being secured to the inclined surface of the wagon bottom, all of said parts secured into an integral structure.

In testimony whereof I have hereunto set my hand in the presence of the subscribing witnesses, on this 29th day of October A. D. 1912.

JOSEPH LEDWINKA.
